UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITION-DYNAMO.

1,226,233.

Specification of Letters Patent.

Patented May 15, 1917.

Application filed June 19, 1915. Serial No. 35,155.

To all whom it may concern:

Be it known that I, CHARLES THOMAS MASON, a citizen of the United States, residing at Sumter, in the county of Sumter and State of South Carolina, have invented certain new and useful Improvements in Ignition-DYNAMOS, of which the following is a specification, reference being had to the accompanying drawing.

10 My invention relates to methods of and apparatus for generating and distributing electric current, and more particularly to such methods and apparatus as applied to ignition systems for internal combustion engines. It has for its object the production of high tension currents under perfect control, and their distribution among a plurality of translating devices such as the spark plugs of a gas engine, in a simple and efficient manner. As hereinafter specifically described, the invention is especially useful in connection with gas engines having a number of cylinders, and therefore a number of spark plugs, constituting a multiple 25 of four. The principles underlying the invention are such, however, that by making suitable changes in the mechanism employed, they may be applied to other numbers than four and its multiples.

30 Stated in general terms, I attain my object by generating electromotive forces and impressing them upon a unitary circuit which in operation becomes sequentially connected with the translating devices 35 through a method of multiple selection, involving their circuits in groups and as units. In order to perform the multiple selections simultaneously, which is desirable for several reasons to be hereinafter pointed 40 out, I treat the individual circuits as units for all purposes; that is to say, I determine the group to be selected at any given instant, and simultaneously determine the unit in that group, leaving all other groups and all 45 other units in that group unaffected, so that only the selected unit in the selected group has its potential raised at that instant. It is possible in this way, by introducing a double gap between the trunk conductor and 50 any idle translating device, to greatly lessen the liability of leakage or of sparks jumping to terminals for which they are not intended.

Stated in terms of apparatus, electromo-

tive force generated by any suitable agency, 55 such as the winding of a magneto, is impressed upon a trunk conductor in a distributor having multiple sets of fixed distributing terminals, and as many connected pairs of traveling terminals as there are sets of 60 fixed terminals. Coöperating with one traveling terminal of each of the pairs, are fixed terminals connected in parallel to the trunk conductor, while the other traveling terminals of the several pairs coöperate with the 65 unit terminals of the respective distributing sets or groups. Thus, in a distributor designed for an eight cylinder engine, I may conveniently arrange the fixed distributing terminals in two groups of four, and terminate the trunk conductor on a parallel-connected group of four fixed terminals; and finally arrange the traveling elements in two 70 pairs, each having one terminal coöperating with the fixed terminals of the trunk conductor, and the other terminal with the fixed terminals of one of the distributing groups. By properly relating the various 75 terminals, the traveling pairs are caused to sequentially connect the unit terminals of 80 the trunk conductor with the unit terminals of one or the other group, but only one of each at a time.

It will be apparent after very slight study of the principle here presented, that it may 85 be applied to distribution among various numbers of sets of terminals, each consisting of a desired number of units. Also this method of distribution may be practised with a variety of machines, and even by 90 hand. A striking advantage flowing from the simultaneous selection of groups (through the trunk conductor terminals) and of units in the groups (through the traveling pairs), is the introduction of a 95 double gap, due to the fact that when one terminal of a traveling pair is moving away from a fixed trunk terminal, the corresponding terminal of the same traveling pair is also moving away from the unit terminal in the group appertaining to said trunk terminal. Only one of these gaps is present in an ordinary distributor, and if we indicate its extent or the resistance introduced into the circuit thereby, as x , and the extent of 100 the second gap in the present case by y , then of course the total gap provided by the present invention is $x+y$. If the mechani-

cal arrangement is such as to permit all fixed terminals to be placed the same distance apart, then the gap would increase to $2x$ as a maximum. The effect of this is to double the efficiency of the device as compared with previous distributor; or if for manufacturing reasons it be desired to reduce the dimensions of the device, this may still be done with an actual increase in efficiency, and an increase in the spacing of the safety gap.

My invention is illustrated in the accompanying drawings in which—

Figure 1 is a vertical sectional view through a complete generating unit adapted to firing an eight cylinder engine, or for any other purpose in which eight sparking circuits are to be supplied in succession. This figure shows all the parts of the generator, and also assembled thereon the interrupter and the distributor.

Fig. 2 is an end elevation of the complete unit shown in Fig. 1, looking in the direction of the arrow above the latter.

Figs. 3, 4, 5 and 6 are respectively a perspective view, a plan view, an end elevation, and a side elevation of the housing for the rotor of the generator, showing particularly the arrangement of the pole faces of the armature or coil structure.

Figs. 7 and 8 are respectively a front elevation with the cap removed, and a side elevation with the cap in section, of the interrupter shown with the cap on in the lower part of Fig. 2.

Fig. 9 is a perspective view of the complete machine with the cap or fixed part of the interrupter detached and supported in reverse position to show the fixed terminals within it.

Referring to the drawings, I shall indicate the generator *per se*, without the interrupter and distributor, by the letter G, and all of its parts by the letter *g* with distinguishing numerical exponents. Similarly, I shall indicate the interrupter as a whole by the letter I and its several parts by the letter *i* with distinguishing numerical exponents; and I shall indicate the distributor as a whole by the letter D and its several parts by the letter *d* with distinguishing numerical exponents.

The generator which has been selected for use in this assembly with my improved system of distribution is of the general type for which I have received Letters Patent of the United States Nos. 1,081,760, granted Dec. 16, 1913, 1,105,361, granted July 28, 1914, and 1,126,676, granted January 26, 1915.

It is to be understood that other types of generator may be used in the present combination, or in other words, that the distributor, the system and the method of distribution, as also the interrupter herein described, may be applied to other types of

generator than that shown. Nevertheless, there are some features in this specific generator which adapt it particularly for its present use, which features containing novelty will be claimed.

The generator comprises three principal parts, viz. the field conveniently composed of permanent magnets *g'*, the rotor composed of two flux carrying elements *g²* and *g³* supported upon a shaft *g⁴*—*g⁵*, and an armature or coil structure composed of the core *g⁶* bridging across laminated pole pieces *g⁷* and *g⁸* and carrying a winding *g⁹* and condenser *g¹⁰*, which, however, will not be broadly claimed herein as it is described and claimed in my prior Patent No. 1,105,361, granted July 28, 1914. The coil also carries an arc-shaped contact *g¹¹* (Figs. 1 and 5) mounted upon an insulating bridge *g¹²* extending between the heads of the magnet. This contact *g¹¹* has a tongue *g¹³* which extends downwardly into proximity with the metal frame, to form a safety gap. In general this feature is the same as shown in my prior application filed January 25, 1915, Serial No. 4357, the functions of the arc-shaped contact and the tongue being the same in both cases, and the general features of the machines throughout being the same, although they differ in matters of detail. The principal difference between the arrangement of the coil contacts in said application and in the present case is that my present distributor carries a common terminal or trunk conductor which makes direct contact with the arc-shaped terminal *g¹¹* on the coil, whereby the necessity for intermediate wiring and insulation is avoided.

The shaft ends *g⁴* and *g⁵* are preferably connected by a non-magnetic block *g¹⁴* to which they are secured by pins *g¹⁵* and *g¹⁶*, as indicated in dotted lines in Fig. 1. The shaft ends extend in opposite directions through sleeves *g¹⁷* and *g¹⁸*, outside of which they carry ball races *g¹⁹* and *g²⁰* constituting portions of ball bearings the other parts of which are carried on the frame of the machine. It will be observed that the shafts *g⁴* and *g⁵* extend through openings in the field magnets, and that the rotor elements are embraced between the field magnet poles, each element constituting a movable pole piece and each being in continuous conductive magnetic relation with its own magnet pole through the sleeve *g¹⁷* or *g¹⁸*, these sleeves being of iron or equivalent material.

The rotor elements are formed in U-shape and are arranged with their arms in quadrature. Inasmuch as the flux must pass from a north to a south pole and vice versa, the fixed poles *g⁷* and *g⁸* are exposed in quadrature to the action of these elements, in the angular relation which is best shown in Fig. 5. Here the exposed face of the pole *g⁷* is marked *g⁷⁰*, and similarly the exposed face of

the pole g^8 is marked g^{80} . With this arrangement, as each diverse pair of poles passes the fixed polar faces g^{70} and g^{80} , a reversal of flux through the coil takes place. Obviously the 5 number of such reversals can be increased by increasing the number of rotor poles and decreasing the angle of separation of the fixed polar faces g^{70} and g^{80} of the armature structure.

10 One terminal of the generating coil being the arc g^{11} , the other terminal is grounded on the frame. In order that the open terminal g^{11} shall be properly controlled by the circuit breaker for short circuiting except at 15 the instant of each break, I carry a conductor g^{21} from the winding of the coil down beneath the armature structure and through a slot in the side of the frame of the machine, into the interrupter box I. This conductor g^{21} may be and preferably is protected by a rigid envelop or casing of some kind, but I make no claim thereto in this case, as the same is described and claimed in 20 my application Serial No. 4357 hereinabove referred to.

The poles g^7 and g^8 are embedded in a cylindrical casting of non-magnetic metal, such as brass or so-called white metal or the like, this being indicated in Figs. 3 and 5 by the 25 letter g^{22} . This casting constitutes a housing for the rotor elements complete excepting at its upper portion marked g^{23} where an air gap is left for the purpose of preventing eddy currents and undue heating. This gap or opening as indicated by the 30 screw holes in Fig. 4 is adapted to be closed by a cover of non-conducting material such as fiber or mica.

The interrupter I is shown in section in 40 Fig. 1, and in elevation with the cap in place in Fig. 2. It is best shown in Figs. 7 and 8, wherein it is supposed to be detached from the magneto. It comprises a fixed contact piece or anvil i' and a movable contact lever i^2 pivoted to the base at i^3 and held in 45 place by the end of a spring i^{30} itself secured to the base at i^{31} , said lever carrying a fiber bumper i^4 , with an operating cam i^5 mounted on the end of and rotating with the rotor 50 shaft g^5 of the generator. A fixed contact i' is set adjustably in one end of the anvil i' , the latter being substantially arc-shaped and forming the terminal of the conductor g^{21} leading from the primary winding of the 55 coil as heretofore described. A mate contact i^8 on the lever i^2 is normally pressed against the fixed contact i' by the spring i^6 , but is removed therefrom to produce a break as the cam i^5 operates upon the bumper i^4 . 60 In the present case this cam has four elevations and four depressions around its periphery, and these are properly positioned with respect to the four arms of the rotor elements g^2 and g^3 , so that the breaks will 65 occur at the proper points on the E. M. F.

and current waves. It is to be particularly noted that the contact end i^8 of the breaker lever i^2 is so positioned that the rotation of the cam i^5 does not throw oil on the contact points, which are screened. This is a feature of some importance, and I shall therefore claim the same. 70

In order that the device thus described may be readily cut out or disabled when desired, I provide means for grounding the 75 anvil contact piece i' which I believe to be novel and original and which I shall therefore claim. This comprises a contact spring i^9 fastened at its outer end upon the arc-shaped anvil and extending along a radius 80 to the center of the breaker box, being at the same time bent upwardly (as best shown in Figs. 1 and 8) so as to carry its inner extremity away from the operating parts. The cap i^{10} is cup-shaped and fits around a 85 shouldered portion i^{11} of the base of the breaker. On the inside of the head of this cap I provide a contacting strip i^{12} , insulated from the metal of the cap by an underlying strip of insulation, and upon the cap I 90 mount a terminal i^{13} offset from the center which connects with the strips i^{12} on the inside of the cap and carries a thumb nut or equivalent device on the outside of the cap for ready attachment of the ground wire i^{14} 95 indicated diagrammatically in Fig. 8 as leading to a grounding switch i^{15} . When this switch is closed, ground is connected through the wire i^{14} , the terminal i^{13} , the strip i^{12} and the spring i^9 to the fixed contact piece or anvil i' . 100

The benefit of this cap construction, with the ground terminal offset from the center, will be understood when it is noted (see Fig. 2) that an ordinary straight spring i^{16} 105 secured at i^{17} to a post on the frame of the machine, is employed to hold the cap in place. This spring cannot well be offset, because the entire breaker structure is rotated through angles indicated by dotted 110 lines in Fig. 2, for purposes of timing, and a balanced pressure for all adjusted positions of the breaker can only be attained at the center of the cap. While this may perhaps be a detail of construction, it is important 115 because a machine of this type is not only run at high speed, but is subject to constant movement and adjustment of its parts, so that the equalizing of strains or pressure and the avoidance of unnecessary wear is 120 absolutely essential throughout.

While I have referred in general terms to the frame of the machine, it is to be understood, in accordance with the principles set forth in my prior Patent No. 1,105,361, filed July 28, 1914, above referred to, that the breaker is really connected to the outer end of the sleeve g^{18} , which projects from the circular flange g^{23} , which with a companion flange g^{24} on the opposite 130

end of the rotor, is secured to the cylindrical housing g^{22} of the rotor which constitutes a part of the armature structure, and carries the poles g^7 and g^8 . The breaker box 5 carries an arm i^{18} by which it may be turned and preferably though not necessarily with it the entire armature structure, so as to partially rotate the polar faces g^{70} and g^{80} around the axis of the rotor. As the angular position of these poles determines the time of peak E. M. F. and current generated in the coil g^9 , the time of breaking the contacts i^7-i^8 corresponds thereto when the parts move together.

5 The distributor D, which as illustrated is especially designed for an eight cylinder engine, is mounted upon the side plate or frame g^{24} of the machine and comprises as its essentials a rotary part d' which is 10 geared to the rotor shaft so as to be actuated therewith, this rotary part carrying circuit distributing terminals which will be more fully described, and a fixed part d^2 upon which are mounted in circular series the groups or fixed contacts constituting terminals of the several distribution circuits, in the present case supposed to be the branch circuits leading to the spark plugs on an eight cylinder engine.

10 The rotary part d' consists of a substantially cylindrical body of insulation d^3 with a substantially cylindrical stem d^4 projecting from one end of the body in the line of its axis. The stem and body are bored from end to end to receive a tubular metallic stem d^5 carrying inner and outer terminals d^6 and d^7 . These terminals may be made adjustable in the stem d^5 , in a variety of ways. They may both be spring pressed plungers, 15 or they may simply be the contact ends of screws tapped into the tube d^5 , or they may be solid terminals of the tube and the latter may be telescoped or otherwise divided at its middle with spring pressure or otherwise to force the two apart. The principal point is to have the two terminals constantly pressed in opposite directions, the inner one d^6 resting against the arc shaped contact g^{11} on the coil structure, and the outer one d^7 resting against a fixed terminal d^8 carried in the cap of the fixed part d^2 .

15 In the body d^3 are formed two radial wells d^9 and d^{11} (see Figs. 1 and 2). In these wells are placed plunger contacts or brushes d^{10} and d^{12} pressed outwardly by suitable springs, and preferably sliding in metallic cylindrical casings set into the wells. As shown in Fig. 2, these two wells and their brushes are angularly displaced for purposes which will be presently explained, and as shown in Fig. 1, they are also set in different planes along the axis of the cylinder, so that they will trace separate circles around the inside of the fixed part d^2 . The fixed terminals carried by the

fixed part d^2 are ranged around these circles in two groups, of four terminals each, the distribution of these terminals around each circle being well shown in Fig. 2, and the spacing apart of the two circles along the 70 axis of the cylinder being indicated in Fig. 1. The brush d^{10} sweeps over the inner ends of one circular set of fixed terminals and the brush d^{12} sweeps over the inner ends of the other circular set. These two brushes, it should now be explained, are angularly displaced from each other, as shown in Fig. 2 in dotted lines, to such a degree that when either one of them is in contact with a terminal in its appropriate group or set, the other brush will be midway between two terminals of its set. These two brushes, d^{10} and d^{12} both carry current, but by means which will be hereafter detailed, each of the brushes is dead when the other is connected to the trunk 80 conductor or stem d^5 and therethrough to the terminal g^{11} of the generating coil. The trunk conductor is connected alternately to one brush and then to the other, hence current is fed alternately to a terminal of one 85 set and then to a terminal of the other, these terminals following each other as the part d' rotates.

The means for alternating the connection of the two brushes to the generator is as 90 follows:

95 Embedded in the cap of the fixed part d^2 are four fixed terminals d^{13} , d^{14} , d^{15} , d^{16} , all of which are connected as indicated at d^{17} in Fig. 1, to a central stem d^{18} , carrying at its 100 inner end the exposed central terminal d^8 , shown as slightly cupped out to receive the outer contact of the metallic tube or stem d^5 . Thus, all four of the contacts d^{13} , d^{14} , d^{15} , d^{16} , are alive during all the time that the 105 generator is running. They are connected to the brushes d^{10} and d^{12} , however, only one at a time. For this purpose I form in the end of the body d^3 two wells d^{19} and d^{20} , in which I place brushes d^{21} and d^{22} . This last 110 brush d^{22} and its well as shown happen to be in coincidence with the contact d^{15} , but the brush d^{21} and its well are midway between two of the contacts, just as the brush d^{10} is midway between two of the circularly 115 arranged terminals on the outside of the fixed part d^2 . The wells d^{19} and d^{20} are also supposed to be lined with metal tubes and these tubes and through them their respective brushes, are respectively and singly connected, to the tubes and brushes d^9-d^{10} and $d^{11}-d^{12}$. When the parts are in the position shown in the drawing, therefore, a circuit is complete from the coil through the contact g^{11} of Fig. 1, through the stem d^5 , 125 and the contact d^7 , to the central fixed contact d^8 , then to contact d^{15} , to the brush d^{22} , thence to the brush d^{12} and thence to the particular terminal on the end set with which brush d^{12} at that instant is in contact, 130

and thence through the distribution circuit to the spark plug or other device thus selectively determined.

Not all of the fixed terminals in the outer shell of the distributor are shown in the drawing. Four of them, however, in the outside or end set are shown in Fig. 2 and are marked d^{23} , d^{24} , d^{25} and d^{26} . Those in the inner circle next to the machine correspond to these in their angular position around the cylinder and are swept over by the brush d^{10} .

The mechanical connections in the distributor for driving purposes are through the gear d^{27} and the pinion g^{25} to the shaft g^5 of the rotor. The ratio of gearing for the eight cylinder machine shown, is two to one, that is to say, the movable member d' of the distributor is driven at a speed one-half that of the rotor of the generator. The rotor may in practice be driven at 3000 revolutions per minute, whereby the gear d^{27} and the movable part d' of the distributor will be driven at the rate of 1500 revolutions per minute. Thus, inasmuch as there are four reversals of flux and four corresponding E. M. F. and current waves in the coil, for each complete revolution of the rotor, there will be eight such reversals and current waves for each rotation of the distributor. There are eight contacts on the distributor in two sets of four each as hereinbefore described; and brief consideration will show that the brushes d^{10} and d^{12} , with their ancillary brushes d^{21} and d^{22} , will during each revolution of the distributor complete a connection from the trunk conductor or stem d^3 to each one of the eight fixed terminals d^{23} , d^{24} , d^{25} , d^{26} , etc., in succession.

Very particular attention is called to the fact that two gaps are introduced between the trunk terminal d^3 and each one of the terminals d^{23} , d^{24} , etc., when the latter is disconnected. One of these gaps is between the end brush d^{21} or d^{22} , and the fixed terminal d^{13} , d^{14} , d^{15} or d^{16} , which it has left or which it has not yet reached; and the other gap is between the brush d^{10} or d^{12} , and the distribution terminal in the circular set, which it has just left or which it has not yet reached. In an ordinary distributor, if we represent the gap between the moving contact and any fixed contact by x , and if the amount of resistance opposed to the jumping of a spark at any instant is proportioned to the angular displacement, then in the present case we may represent this resistance by $x+y$, y representing the second gap which I have introduced. I have shown the brushes d^{21} and d^{22} in the ends of the rotating part of the distributor, so that the angular distance between the brushes and the terminals is not quite as great at their maximum as the distance between the peripheral branches d^{10} and d^{12} .

and their respective terminals; but I am not limited to this arrangement, as the brushes d^{21} and d^{22} may also be made peripheral by lengthening the cylinder d^3 . In such case the quantity y would become equal to x and the resistance of the gaps to an abnormal discharge or jump of the spark between terminals would be $2x$ or double what is obtainable in an ordinary type of distributor. Another point I emphasize is this, that the brushes and terminals are all embedded in insulation, the design of all the parts being such that even the distribution terminals d^{23} , d^{24} , etc., are or may be completely covered and protected by insulating material. Possibility of short circuiting or of jumping of the sparks is therefore reduced to a minimum, and the high tension current which I generate and employ in this machine is as free from accidental diversion or shunting as that of an ordinary low tension machine.

The pinion g^{25} and the gear wheel d^{27} are inclosed in a cast frame g^{24} , which is best shown in Fig. 9, the fixed part or shell of the distributor in said figure being removed and set to one side with its open end presented to the observer. Set around the periphery of the upper part of this frame are three clamps g^{26} , which in Fig. 2 are shown in position to hold the shell of the distributor in place, and in Fig. 9 are shown slackened off to permit the removal of the shell. The shell when in position exerts pressure through contact d^8 upon the end of the terminal d^7 (see Fig. 1), and thereby holds the movable part in position, with its stem extending through the tubular hub of the gearing and bushing, through the frame and through the bushed opening so that the inner contact d^6 is held firmly against the arc contact g^{11} on the coil. The mechanical connection between the body d^3 of the removable member of the distributor and the gear d^{27} by which it is turned, is through a bushing or metal ring d^{30} , carrying projecting pins or studs d^{31} , which engage in sockets in the body when the latter is placed in position, the ring lying in an annular channel in the body outside of which the latter has a flange which rests against the face of the gear d^{27} . The ring d^{30} forms a part of a hollow hub d^{32} , which rotates inside the bearing sleeve on the frame, the arrangement of the journal bearings, however, being a detail which forms no part of the present invention. The ring d^{30} is conveniently secured to the gear d^{27} by means of screws which may pass from either part into the other.

It will be apparent from the foregoing description and a casual inspection of Figs. 1, 2 and 9, that by merely slackening off the clamps g^{26} , the shell or fixed part of the distributor may be removed with all of the

distributing contacts d^{23} , d^{24} , etc., and there being nothing then to hold the rotary part in position, the latter may be removed by simply pulling out its stem d^4 from the hollow hub or bushing d^{32} , the body then coming off the pins d^{31} and the gear remaining exposed.

Of course some changes in detail may be made in this arrangement without departing from the scope of the invention and I have described the specific arrangement for the benefit of those who may wish to practise the invention when free to do so, and not for purposes of limitation. I find it very convenient, especially when adapting this device to more than eight cylinders, to cut away all superfluous material from the body d^3 , leaving only a central cylinder or hub, and enough insulating material projecting therefrom in radial masses to furnish bodies in which to embed the brush contacts d^{10} , d^{12} , d^{21} and d^{22} , and to furnish perhaps a screen between any two points which have a large difference of potential, such points for example being the distribution contacts d^{23} , d^{24} , etc., and the contact d^8 in the cap. This concludes the description of an eight cylinder magneto embodying my invention. I wish to point out, however, very briefly, the method by which the same principles may be applied to a twelve cylinder or other multi-circuit engine.

It is apparent that the total number of cylinders is a multiple of the number of flux reversals produced by the rotor in each revolution. As heretofore described, with two U-shaped elements and four flux reversals per revolution, the distributor being driven at one-half the speed of the rotor, we have eight E. M. F. and current wave peaks per revolution of the distributor. Now, for a twelve cylinder engine, we must have 12 current peaks per revolution of the distributor, and these may be produced in either one of two ways, viz. (a) by increasing the number of prongs on each element of the rotor to three instead of two, so that the two elements of the rotor interlock like two three-pronged forks with their prongs alternating, whereby there will be actually six reversals of flux per revolution, because there are six pairs of opposite poles presented in a ring around the rotor. By gearing the distributor still as two to one, the rotor will make two complete revolutions for each one revolution of the distributor and we shall therefore have twelve complete current changes per revolution of the distributor. To take advantage of these, and distribute them properly, it is only necessary to set the distribution terminals d^{23} , d^{24} , etc., around the distributor shell with six in each circle instead of four, and to increase the number of co-operating cap terminals d^{13} , d^{14} , d^{15} , d^{16} to six instead of

four. (b) The second method of changing to a twelve cylinder device which I use in practice is to leave the rotor elements exactly as they are shown in Fig. 1, two in number, with double arms producing four flux variations per revolution; and then gear the distributor to the rotor with a ratio of three to one, whereby there will be 12 flux variations in the coil per revolution of the distributor. The distribution terminals d^{23} , d^{24} , etc., would then remain in sets of four around the shell of the distributor but there would have to be three sets or circles of these contacts instead of two, three brushes like d^{10} and d^{12} instead of two, and three end brushes like d^{21} and d^{22} instead of two. In setting these end brushes, instead of each brush contacting when the following brush is half way between terminals, the space between terminals would have to be divided by three, since there are three pairs of brushes. Thus brush No. 1 would make contact when No. 2 was one-third back of it, and No. 3 brush two-thirds back of it.

The description of the generator coil g^9 hereinbefore given, should be supplemented by the following explanation: This being a high tension machine, the coil in question carries primary and secondary windings. The condenser g^{10} has one of its terminals g^{100} connected to one terminal of the primary winding of the coil, and while this arrangement is shown and described herein for convenience, it should be understood that it constitutes a separate invention and has been made the subject matter of description and claims in another case. The secondary winding of the coil, which is a high tension winding, has one terminal grounded on the frame and the other terminal connected to the carefully insulated contact g^{11} . It is the high tension current from the secondary winding which is conveyed through the stem conductor d^6 , and distributed among the distribution terminals d^{23} , etc. The function of the interrupter as will be readily understood, is fundamentally the same as that of any ordinary interrupter, maintaining the discharge circuit disabled or shunted until the discharge point is reached and then breaking the shunt.

Having thus described my invention what I claim and desire to secure by Letters Patent is—

1. The method of distributing ignition current from a trunk point to a plurality of spark devices which consists in providing a plurality of groups of two or more units individually connected to the respective spark devices, and selecting first one group of units and then another and simultaneously connecting a selected unit in said group to said trunk point.

2. The method of distributing ignition current from a trunk point to a plurality of

spark devices which consists in arranging the receiving terminals for the spark devices in groups of two or more and selecting first one group of terminals and then another and simultaneously connecting a unit terminal in said group with a unit terminal in a series of mechanically separated but electrically connected contacts connected with said trunk point.

- 10 3. In the method of distributing ignition current from a trunk point to a plurality of spark devices of an internal combustion engine which consists in arranging the receiving terminals for the respective spark devices in a plurality of groups of two or more, and simultaneously selecting one of said groups at a time and connecting a unit terminal therein with an associated unit contact in a series of mechanically separated but electrically connected contacts connected to said trunk conductor.

4. A system for generation and distribution of electric currents among a plurality of translating devices in determinate order, comprising the following instrumentalities: a source of electromotive force and current, a common trunk conductor connected thereto, a plurality of selective terminals mechanically separated but electrically connected to said trunk conductor, a plurality of groups or sets of selective terminals each corresponding to one of the selective terminals connected with the trunk conductor, and each group containing a number of separate unit terminals severally connected to determinate unit translating devices, and co-operating selective terminals in pairs, the number of pairs corresponding to the number of groups or sets of translating device terminals, said pairs having simultaneous relative motion with respect to the several selective terminals, and each pair consisting of one terminal adapted to coöperate with the selective terminals of the trunk conductor, while its associated terminal coöperates with the unit terminals of the particular group or set to which the pair corresponds.

5. A system for generation and distribution of electric currents among a plurality of translating devices in determinate order, comprising the following instrumentalities: a source of electromotive force and current, a trunk conductor connected to said source, and a distributor containing a plurality of fixed terminals mechanically separated but all electrically connected to said trunk conductor, a plurality of groups or sets each composed of a plurality of fixed unit terminals connected to determinate translating devices, and a plurality of traveling pairs of terminals, one pair for each group or set of unit terminals, each pair having one terminal adapted to travel over and sequentially effect contact with terminals of the trunk conductor, while the associated terminal of

the pair travels over and simultaneously and successively effects contact with determinate unit terminals of its group or set.

6. A system for generation and distribution of electric currents among a plurality of translating devices in determinate order, comprising the following instrumentalities: a source of electromotive force and current, a trunk conductor connected to said source, and a distributor containing a plurality of fixed terminals mechanically separated but all electrically connected to said trunk conductor, a plurality of groups or sets each composed of a plurality of fixed unit terminals connected to determinate translating devices, and a plurality of traveling pairs of terminals, one pair for each group or set of unit terminals, each pair having one terminal adapted to travel over and sequentially effect contact with terminals of the trunk conductor, while the associated terminal of the pair travels over and simultaneously and successively effects contact with determinate unit terminals of its group or set, together with means for supporting and driving said traveling pairs so that only one pair will make contact at the same time.

7. A system for generation and distribution of electric currents among a plurality of translating devices in determinate order, comprising the following instrumentalities: a source of electromotive force and current, a trunk conductor connected to said source, and a distributor containing a plurality of fixed terminals mechanically separated but all electrically connected to said trunk conductor, a plurality of groups or sets each composed of a plurality of fixed unit terminals connected to determinate translating devices, and a plurality of traveling pairs of terminals, one pair for each group or set of unit terminals, each pair having one terminal adapted to travel over and sequentially effect contact with terminals of the trunk conductor, while the associated terminal of the pair travels over and simultaneously and successively effects contact with determinate unit terminals of its group or set, together with means for supporting and driving said traveling pairs so that each pair will make and break both its contacts simultaneously, and the two pairs will make and break alternately.

8. A system for generation and distribution of electric currents among a plurality of translating devices in determinate order, comprising the following instrumentalities: a source of current, a trunk conductor connected to said source, and a distributor comprising a rotary part and fixed circuit terminals arranged in a plurality of sets, one set connected in parallel to the trunk conductor, and the terminals of each of the other sets being individually and separately connected to unit translating devices, the

terminals in all of the sets being angularly spaced relative to each other around the axis of the rotary part, and a plurality of traveling connected pairs of contacts carried by the rotary part of the distributor, the pairs being angularly displaced from each other, and the contacts in each pair being arranged so that one contact will sweep over the set of terminals connected to the trunk conductor while the other contact of the pair will sweep over the terminals of one particular set.

9. A system for generation and distribution of electric currents among a plurality of translating devices in determinate order, comprising the following instrumentalities: a source of current, a trunk conductor connected to said source, and a distributor comprising a rotary part and fixed circuit terminals arranged in a plurality of sets, one set connected in parallel to the trunk conductor, and the terminals of each of the other sets being individually and separately connected to unit translating devices, the terminals in all of the sets being angularly spaced relative to each other around the axis of the rotary part, and a plurality of traveling connected pairs of contacts carried by the rotary part of the distributor, the pairs being angularly displaced from each other, and the contacts in each pair being arranged so that one contact will sweep over the set of terminals connected to the trunk conductor while the other contact of the pair will sweep over the terminals of one particular set, make and break contacts by the two connected elements of each traveling pair being simultaneous, whereby the trunk conductor and the source of current will be connected at any given instant through one pair only to one selected terminal in one selected set of the translating devices.

10. A system for generation and distribution of electric currents among a plurality of translating devices in determinate order, comprising the following instrumentalities: a source of current, a trunk conductor connected thereto, and a distributor comprising a fixed shell and a driven rotor centered with respect to the shell, a plurality of sets of distributing terminals supported upon said shell in circles spaced apart from each other, a circular series of fixed terminals also supported on the shell and all connected to said trunk conductor, a plurality of insulated brush contacts on the rotor, each adapted to sweep over one determinate circle or arc of distributing terminals and no other, a corresponding number of insulated brush contacts angularly displaced from each other, but all arranged to sweep over the circle or arc of terminals connected to the trunk conductor, and means connecting said brush contacts in pairs,

each pair adapted in the course of its travel with the rotor to connect the trunk conductor through one of its terminals to one or the other of the unit terminals in one of the distributing sets.

11. In a system of the class described, a distributor comprising a cylindrical shell and a driven rotor element axially centered therein, a plurality of sets of distributing terminals arranged on circles spaced apart along the shell, a number of live or current terminals electrically connected together, common to the sets of distributing terminals but on a circle spaced apart therefrom, a brush contact carried by the rotor element for and adapted to sweep over, each of the sets of distributing terminals, and connected terminals carried by the rotor element adapted to successively connect the live terminals to unit terminals in the several distributing sets.

12. In a system of the class described, a distributor comprising a cylindrical shell and a driven rotor element axially centered therein, a plurality of sets of distributing terminals arranged on circles spaced apart along the shell, a number of live or current terminals electrically connected together, common to the sets of distributing terminals but on a circle spaced apart therefrom, a brush contact carried by the rotor element for, and adapted to sweep over, each of the sets of distributing terminals, and a plurality of associated brush terminals, one for each of the first named brush contacts connected thereto to form a pair, all sweeping over the live terminals as the rotor member rotates, the pairs being relatively arranged so as to alternate in their connection of the live terminals with the distributing terminals.

13. In a system of the class described, a source of current, a current terminal therefor, and a distributor comprising the following instrumentalities: a cylindrical shell having one end open and one end closed to form a head, a plurality of distributing terminals in sets carried on the shell in circles spaced apart from its head and from each other, a set of live or current terminals arranged on a circle upon the head, and a plurality of pairs of brush contacts corresponding in number to the number of sets of distributing terminals, the brush contacts of each pair adapted in their sweep to successively connect the live terminals to the unit terminals in the set to which the pair corresponds.

14. In a system of the class described, a distributor having fixed and movable elements, and fixed circuit terminals arranged in a plurality of sets, with means carried by said movable element to successively connect terminals in one set with terminals in other sets.

15. In a system of the class described, a current generator, driving means therefor, and a distributor secured upon the generator and adapted to be actuated from its driving means, comprising the following instrumentalities: a cylindrical shell carrying a plurality of sets of distributing terminals on circles axially spaced apart along the cylinder, live or current terminals in the head of the cylinder, a rotary element within the cylinder, peripheral brushes carried on said rotary element, one for each set of distributing terminals and each adapted in its rotation to sweep over the exposed ends of its set of terminals within the cylinder, and end brushes carried on said rotary element sweeping over said live terminals in common, each end brush connected to one of the peripheral brushes.
- 10 16. In a system of the class described, a current generator, driving means therefor, and a distributor secured upon the generator and adapted to be actuated from its driving means, comprising the following instrumentalities: a cylindrical shell carrying a plurality of sets of distributing terminals on circles axially spaced apart along the cylinder, live or current terminals in the head of the cylinder, a rotary element within the cylinder, peripheral brushes carried on said rotary element, one for each set of distributing terminals and each adapted in its rotation to sweep over the exposed ends of its set of terminals within the cylinder, and end brushes carried on said rotary element sweeping over said live terminals in common, each end brush connected to one of the peripheral brushes, and angularly displaced from the other end brush or brushes, whereby no two distributing terminals and no two sets of distributing terminals can be connected to the current terminals at the same time.
- 11 17. In combination, a generator having a driving shaft, and a distributor comprising the following instrumentalities: a rotary element geared to said driving shaft, a fixed element surrounding said rotary element and carrying peripheral and end terminals, and means on the rotary element to make and break double contacts in the same circuit between said end and peripheral terminals.
- 12 18. In a system of the class described, means for generating high tension current, and a distributor associated therewith containing terminals for a plurality of distribution circuits, and a terminal for the generating means, together with means for building up a connection and breaking the same through a plurality of contacts in series between the generating terminal and any one of the distributing terminals.
- 13 19. In a system of the class described, means for generating high tension current, and a distributor associated therewith containing terminals for a plurality of distribution circuits, and a terminal for the generating means, together with means for building up a connection and breaking the same through a plurality of contacts in series between the generating terminal and any one of the distributing terminals, said contacts acting to open simultaneously.
- 14 20. In a system of the class described, means for generating high tension current, and a distributor associated therewith containing terminals for a plurality of distribution circuits, and a terminal for the generating means, together with means for building up a connection and breaking the same through a plurality of contacts in series between the generating terminal and any one of the distributing terminals, said contacts acting to open and close simultaneously, and the several terminals being so related that closing of any path to a distributing circuit cannot be effected until both gaps in series in the preceding path to another terminal are opened to their maximum extent.
- 15 21. In a system of the class described, a support, a generator terminal, a driving gear mounted on said support with a free opening through its center, and a distributor having a rotary member provided with a body and a central projecting stem extending through the central opening in said gear, and a fixed member holding the rotary member in position, coöperating contacts on said fixed and rotary members, and a circuit connection from the generator terminals to said contacts, extending through the central stem of the rotary member.
- 16 22. In a system of the class described, a support, a generator terminal, a driving gear mounted on said support with a free opening through its center, and a distributor having a rotary member provided with a body and a central projecting stem extending through the central opening in said gear, and a fixed member holding the rotary member in position, coöperating contacts on said fixed and rotary members, and a circuit connector having a contact brush on its inner end bearing against the generator terminal, and extending through the axis of the rotary member and its stem to the interrupter contacts.
- 17 23. In a system of the class described, a generator, a winding thereon having an exposed terminal, and a detachable interrupter having the current or supply side of its circuit terminating in an exposed brush terminal arranged so as to automatically make contact with the generator terminal when the interrupter is secured in position, and to automatically break contact when the interrupter is detached.
- 18 24. In a system of the class described, a

generator, a winding thereon having an exposed terminal, means for driving said generator, a gear wheel also driven from said means, and a detachable distributor comprising the following instrumentalities: a rotary member having a cylindrical body of insulating material and an axially projecting stem adapted to be passed through the open center of said gear wheel, so that the body will engage and turn therewith, a metal conductor extending from end to end through the stem and body of the rotary member and terminating in yielding brush contacts at both ends, the contact at the stem end when the member is in position on the gear wheel, making contact with the generator terminal; and a shell or fixed member carrying fixed distributing terminals and a fixed current terminal embedded in its body with their inside faces exposed, the current terminal being located in the end or head of the cylinder overlying the outer end of the rotary member of the distributor, and normally making contact with the outer brush on the central conductor of the rotary member, the arrangement being such that normally current passes from the generator terminal through the center of the rotary member to the current terminal on the shell, thence through coöperating contacts on the rotary member to the appropriate fixed contacts in the sides of the shell.

25. In a system of the class described, a dynamo including a rotor, a winding separate therefrom and having an exposed terminal, and a distributor having a coöperating contact terminal, both terminals being movable, but adapted to maintain contact with each other during their respective movements.

26. In a system of the class described, a dynamo having a part adjustable for timing the peak of its E. M. F. curve, a collector terminal carried on said adjustable part, and a distributor having a coöperating brush terminal adapted to maintain direct contact with the generator terminal throughout the range of its adjustment.

27. In a system of the class described, a dynamo having a part adjustable for timing purposes, a collector terminal carried on said part and traveling therewith, and a distributor having a fixed and a movable element, the fixed element carrying distributing terminals, and the movable element carrying brush contacts therefor and a separate brush contact engaging said collector terminal on the dynamo throughout the range of their respective movements.

28. In a system of the class described, a dynamo having a part adjustable for timing purposes, an exposed collector terminal carried on said part and having a length equal to the range of adjustment, and an interrupter having fixed and traveling con-

tacts, and a brush terminal therefor engaged by the dynamo contact throughout its range of travel during adjustment.

29. In a system of the class described, a dynamo having a rotor, a winding separate therefrom and with an exposed collector terminal mounted thereon, and a distributor adapted to be attached to the dynamo with a coöperating terminal thereby brought into direct engagement with said collector terminal on the winding. 75

30. In a system of the class described, a dynamo having a rotor, a winding separate therefrom and adjustable for timing purposes, an exposed collector terminal for said winding mounted upon and traveling with it, and a distributor adapted to be attached to said dynamo, with a brush contact thereby brought into engagement with the collector terminal on the winding in such manner as to remain in engagement therewith throughout the range of travel thereof. 80

31. In a system of the class described, a dynamo having an exciting field, an armature structure, a rotor, and a generating winding on the armature structure, said structure being adjustable around the rotor for timing purposes, an arc-shaped exposed collector terminal carried on the winding, and a distributor adapted to be secured upon the machine, with a brush contact on said distributor directly engaging said arc-shaped terminal on the winding, and maintaining such engagement throughout the range of timing adjustment. 90

32. A distributor for high tension ignition systems comprising a cylindrical shell of insulating material, distributing terminals in circular arrangement around the shell and embedded in the insulating material, with their ends exposed around the inner surface of the shell, a substantially cylindrical rotary member of insulating material within the shell, having a lateral recess in its body and a brush terminal located therein with its end adapted to sweep around the inner surface of the shell over the exposed faces of the distributing terminals, and insulating conducting means adapted to convey current to said brush terminal. 105

33. A distributor for high tension ignition systems comprising a cylindrical shell of insulating material, distributing terminals in circular arrangement around the shell and embedded in the insulating material, with their ends exposed around the inner surface of the shell, a substantially cylindrical rotary member of insulating material within the shell, having a lateral recess in its body and a brush terminal located therein with its end adapted to sweep around the inner surface of the shell over the exposed faces of the distributing terminals, and a conductor extending through 110

the body of the rotary member; together with means connecting the same to the brush terminal.

34. A distributor for high tension ignition systems comprising a cylindrical shell of insulating material, distributing terminals in circular arrangement around the shell and embedded in the insulating material, with their ends exposed around the inner surface of the shell, a substantially cylindrical rotary member of insulating material within the shell, having a lateral recess in its body and a brush terminal located therein with its end adapted to sweep around the inner surface of the shell over the exposed faces of the distributing terminals, together with coöperating insulated contacts in the end of the rotary member and on the adjacent head of the shell, to connect said conductor to the brush terminal.

35. A distributor for high tension ignition systems comprising a cylindrical shell of insulating material with one end closed and the other end open, a cylindrical rotor also of insulating material extending into the open end of the shell, a plurality of sets of distributing terminals each set arranged in a circle around the outside of the shell with the unit terminals extending radially through the wall of the shell so as to expose their ends around the inner face thereof, and the several sets being in planes spaced apart from each other along the cylinder, radial recesses extending into the insulating body of the rotary member one for each set of distributing terminals, and a brush in each recess with its head in position to sweep around over its own set of distributing terminals only, a trunk conductor conveying current to the distributor, and a plurality of terminals embedded in the head of the shell, with their ends exposed on the inner face thereof and all connected in parallel to said trunk conductor, a number of recesses in the end of the rotary member corresponding to the number of lateral recesses and the number of sets of distributing terminals, and brushes seated in said end recesses adapted to sweep over the exposed ends of the current-carrying terminals in the head of the shell, together with an electrical connection through the body of the rotary member from each of the end brushes to one only of the lateral brushes.

36. In a high tension ignition system, a dynamo carrying a generating winding and a terminal for the same, a rotor and its driving shaft in said dynamo, a frame or support secured upon the dynamo, a gear wheel journaled on a tubular bearing in said frame, coupling means projecting from said gear wheel, and an interrupter comprising a cylindrical shell and a cylindrical rotor therein with an axially projecting stem, said stem extending through the tubular bearing

of the gear wheel and the body engaging said coupling means, distributing terminals around the sides of the shell and coöperating brushes on the rotary member, and a conductor extending through the axis of the body and stem of the rotary member from end to end thereof with spring pressed brushes at its ends, with terminal spring pressed brushes, the brush at the inner end engaging the terminal of the generating winding and the brush on the outer end engaging a contact in the head or end of the shell, with means connecting said contact to the brushes of the rotary member, whereby the shell normally serves to maintain the rotary member in operating engagement with and relation to its driving gear and the terminal of the generating winding, and when detached, permits the removal of the rotary member by simply pulling it away from the gear and removing its stem from the tubular bearing thereof, automatically breaking all electrical connections thereby.

37. In an ignition system, a magneto having a generating coil with one end terminating on an exposed terminal, and a distributor having fixed and movable members, adapted to be detachably secured to the generator with a coöperating contact engaging said coil terminal, said connection between the coil terminal and contact being automatically broken when said distributor members are removed from the magneto.

38. In an ignition system, a magneto having a generating coil and a contact terminal therefor, a rotor and a shaft therefor, a gear driven from said shaft, and a distributor adapted to be driven by said gear and carrying a contact to coöperate with the coil terminal, with means detachably connecting the movable member of said distributor to said gear, and means for connecting the fixed member of the distributor to the frame or support of the machine, the parts being so arranged that the connection between the coil terminal and the contact will be automatically broken when said distributor is removed from the magneto.

39. In an ignition system, a generator having a tubular journal bearing, a bushed gear on said bearing, means for driving the same from the generator shaft, a distributor having a rotary member provided with a body and a centrally projecting stem which is adapted to be plugged into said bush gear and turned therewith, means for retaining the same in position, a fixed member holding said rotary member in position, coöperating contacts on said fixed and rotary members, a circuit connection from the generator terminal to said contacts extending through the central stem of the rotary member.

40. In an ignition system, a generator having an exciting field, a generating coil and a rotor separate from said generating coil and having means to produce a plurality of E. M. F. peaks in said winding for each rotation of the rotor, in combination with a distributor geared to be driven with said rotor and provided with means for dividing and distributing in determinate groups the several currents due to the corresponding E. M. F. changes produced in the generator winding for successive rotations of the rotor.
41. In an ignition system, a generator having an exciting field, a generating winding, and a rotor with a plurality of members each adapted to vary the flux from the field through the winding during each rotation of the rotor, whereby a plurality of 15 symmetically varying E. M. F. and current waves are produced for each rotation, in combination with a distributor geared to be driven with the rotor, and provided with a plurality of groups of distributing terminals, and means to distribute said currents 20 symmetically and successively to said distributing terminals when said current and E. M. F. waves are at a maximum and during the successive rotations of the rotor and 25 the distributor.
42. In an ignition system, a generator having an exciting field, a generating winding, and a rotor with a plurality of members each adapted to vary the flux from the field through the winding during each rotation of the rotor, whereby a plurality of 30 symmetically varying E. M. F. and current waves are produced for each rotation, in combination with a distributor geared to 35 be driven with the rotor, and provided with a plurality of groups of distributing terminals, and means to distribute said currents 40 symmetically and successively to said distributing terminals when said current and E. M. F. waves are at a maximum and during the successive rotations of the rotor and 45 the distributor, together with a circuit breaker also driven with the rotor, and adapted to produce a plurality of breaks and 50 thereby a plurality of discharges from the winding through the distributor, at predetermined points on the several E. M. F. waves, for each rotation of the rotor.
43. In an ignition system, a generator having an exciting field, a generating winding, and a rotor with a plurality of members each adapted to vary the flux from the field through the winding during each rotation of the rotor, whereby a plurality of 55 symmetically varying E. M. F. and current waves are produced for each rotation, in combination with a distributor geared to be driven with the rotor, and provided with a plurality of groups of distributing terminals, and means to distribute said cur- 60 rents symmetrically and successively to said distributing terminals when said current and E. M. F. waves are at a maximum and during the successive rotations of the rotor and the distributor, together with a circuit breaker also driven with the rotor, and adapted to produce a plurality of breaks and thereby a plurality of discharges from the winding through the distributor, at predetermined points on the several E. M. F. waves, for each rotation of the rotor, and means for varying the time of the breaks relatively to their respective E. M. F. waves.
44. In an ignition system, a generator adapted to produce four or more E. M. F. and current waves for each rotation of its rotor, a distributor and a circuit breaker both driven with the rotor, the distributor carrying a plurality of groups of distributing terminals, and means for selecting and distributing the current waves or impulses among the terminals, and a circuit breaker adapted to symmetrically break and thereby cause symmetrical discharges due to the said E. M. F. waves through the circuits successively established by the distributor.
45. In an ignition system, a generator adapted to produce four or more E. M. F. and current waves for each rotation of its rotor, a circuit breaker adapted to produce a corresponding plurality of breaks and discharges for each rotation of the rotor, and a distributor connected and driven so as to distribute the corresponding discharges in successive rotations.
46. In a system of the class described, a dynamo for generating a plurality of current impulses per revolution comprising a fixed exciting field structure, a rotor composed of two members, each formed in U-shape with their open ends overlapped to present alternate poles as the rotor is rotated, a generating coil and a core structure therefor having pole pieces in proximity to the path of travel of said rotor, and means for adjusting said structure and pole pieces around the axis of the rotor whereby all of the current impulses due to the multiple poles of the rotor may be simultaneously timed as to their peaks or sparking points.
47. In a system of the class described, means for generating and distributing current impulses into a plurality of distribution circuits such as the sparking circuits of a multi-cylinder engine, comprising a field, a generating coil, and a rotor rotating in said field and adapted to produce in said coil four or more impulses per revolution, and a distributor electrically connected to the coil and mechanically connected to the rotor through reducing gears, whereby said rotor will make a plurality of revolutions for each single revolution of the distributor, and a number of distribution terminals in said dis-

tributer equal to the whole number of circuits to be served, with means to connect said coil in succession to each one of said terminals during each revolution of the distributer.

48. In a system of the class described, means for generating and distributing current impulses into a plurality of distribution circuits such as the sparking circuits of a multi-cylinder engine, comprising a field, a generating coil, and a rotor rotating in said field and adapted to produce in said coil four or more impulses per revolution, and a distributer electrically connected to the coil and mechanically connected to the rotor through reducing gears, whereby said rotor will make a plurality of revolutions for each single revolution of the distributer, and a number of distribution terminals in said distributer equal to the whole number of circuits to be served, with means to connect said coil in succession to each one of said terminals during each revolution of the distributer, together with means for timing all of the current impulses produced in the coil simultaneously.

49. In a system of the class described, means for generating and distributing current impulses into a plurality of distribution circuits such as the sparking circuits of a multi-cylinder engine, comprising a field, a generating coil, and a rotor rotating in said field and adapted to produce in said coil four or more impulses per revolution, and a distributer electrically connected to the coil and mechanically connected to the rotor through reducing gears, whereby said rotor will make a plurality of revolutions for each single revolution of the distributer, and a number of distribution terminals in said distributer equal to the whole number of circuits to be served, with means to connect said coil in succession to each one of said terminals during each revolution of the distributer, together with means for adjusting the coil and its magnetic structure with respect to the rotor, for simultaneously timing all of the current impulses in the coil.

50. In a system of the class described, means for generating and distributing current impulses into a plurality of distribution circuits such as the sparking circuits of a multi-cylinder engine, comprising a field, a generating coil, and a rotor rotating in said field and adapted to produce in said coil four or more impulses per revolution, and a distributer electrically connected to the coil and mechanically connected to the rotor through reducing gears, whereby said rotor will make a plurality of revolutions for each single revolution of the distributer, and a number of distribution terminals in said distributer equal to the whole number of circuits to be served, with means to connect said coil in succession to each one of said

terminals during each revolution of the distributer, together with an interrupter driven with the rotor and adapted to render the discharge circuit from the coil operative at a predetermined point on the E. M. F. and current wave of each and every impulse produced in the coil.

51. A dynamo for supplying current impulses in succession to a plurality of distributing circuits comprising the following instrumentalities: a field, a rotor and a generating coil, an interrupter mechanically connected with the rotor and electrically connected with the coil, and a distributer mechanically geared to the rotor and electrically connected to the coil, said rotor having means for producing in said coil four or more current impulses per revolution, said interrupter rendering operative the discharge circuit from the coil at a predetermined point on the E. M. F. or current wave of each and every impulse produced in the coil and said distributer through its gears traveling at such a ratio of speed with the rotor that it will combine the impulses from the coil due to a plurality of revolutions of the rotor, and deliver them in a single revolution of the distributer to all of the desired distribution circuits in succession.

52. A dynamo for supplying current impulses in succession to a plurality of distributing circuits comprising the following instrumentalities: a field, a rotor and a generating coil, an interrupter mechanically connected with the rotor and electrically connected with the coil, and a distributer mechanically geared to the rotor and electrically connected to the coil, said rotor having means for producing in said coil four or more current impulses per revolution, said interrupter rendering operative the discharge circuit from the coil at a predetermined point on the E. M. F. or current wave of each and every impulse produced in the coil and said distributer through its gears traveling at such a ratio of speed with the rotor that it will combine the impulses from the coil due to a plurality of revolutions of the rotor, and deliver them in a single revolution of the distributer to all of the desired distribution circuits in succession, together with means for varying at will the point in each revolution of the rotor where the peak E. M. F. will be produced in the coil.

53. A dynamo for supplying current impulses in succession to a plurality of distributing circuits comprising the following instrumentalities: a field, a rotor and a generating coil, an interrupter mechanically connected with the rotor and electrically connected with the coil, and a distributer mechanically geared to the rotor and electrically connected to the coil, said rotor hav-

ing means for producing in said coil four or more current impulses per revolution, said interrupter rendering operative the discharge circuit from the coil at a predetermined point on the E. M. F. or current wave of each and every impulse produced in the coil and said distributor through its gears traveling at such a ratio of speed with the rotor that it will combine the impulses from the 10 coil due to a plurality of revolutions of the rotor, and deliver them in a single revolution of the distributor to all of the desired distributing circuits in succession, together with means for varying at will the point in 15 each revolution of the rotor where the peak E. M. F. will be produced in the coil, and means for simultaneously varying the points in the revolution of the rotor at which the interrupter will render operative the discharge circuit from the coil.

54. In an ignition dynamo for multi-circuit distribution, a field, a generating coil, a rotor having two elements each with a plurality of arms whereby a corresponding plurality of current reversals is produced in the coil at each revolution of the rotor, means for receiving and arranging in sets or groups the current impulses of successive revolutions of the rotor and distributing them 30 among the distribution circuits in one series.

55. In an ignition dynamo for multi-circuit distribution, a field, a generating coil, a rotor having two elements each with a plurality of arms whereby a corresponding plurality of current reversals is produced in the coil at each revolution of the rotor, means for receiving and arranging in sets or groups the current impulses of successive revolutions of the rotor and distributing them 40 among the distribution circuits in one series, said means adapted to select and distribute among the distribution circuits by groups, and unit circuits in a group, the number of groups being the same as the 45 number of revolutions of the rotor for each complete series, and the number of unit or individual circuits in each group being the same as the number of current changes or flux reversals produced in each revolution 50 of the rotor.

56. In an ignition dynamo, a field, a rotor composed of two elements each with a plurality of flux bearing arms, all said arms rotating in succession through a flux varying path, a generating coil, a core for the same, and a pair of pole pieces forming magnetic terminals of said core and lying in an arc adjacent to the path of travel of the rotor elements, the length of said arc 55 and the distance between the centers of the exposed polar faces, being less than 180°, whereby alternate poles of opposite elements in the rotor are successively bridged across said polar faces in alternate reversed directions.

57. In an ignition dynamo, a field, a rotor composed of two elements each with a plurality of flux bearing arms, all said arms rotating in succession through a flux varying path, a generating coil, a core for the same, and a pair of pole pieces forming magnetic terminals of said core and lying in an arc adjacent to the path of travel of the rotor elements, the length of said arc and the distance between the centers of the exposed 70 polar faces, being less than 180°, and corresponding to the angular displacement between each adjacent pair of opposed polar prongs on the respective rotor elements.

58. In an ignition dynamo, a field, a rotor composed of two elements each with a plurality of flux bearing arms, all said arms rotating in succession through a flux varying path, a generating coil, a core for the same, and a pair of pole pieces forming magnetic 80 terminals of said core and lying in an arc adjacent to the path of travel of the rotor elements, the length of said arc and the distance between the centers of the exposed polar faces, being less than 180°, and determined by dividing the total circumference 90 of a circle of 360° into as many parts as there are prongs or polar projections on each of the elements of the rotor.

59. In a system of the class described, a generator having a field, a generating coil and a rotor separate from said coil and adapted to produce with the coil four or more E. M. F. and current waves for each revolution, a distributor adapted to combine 100 and distribute in one series the impulses produced in a plurality of revolutions of the rotor, and an interrupter electrically connected with the coil and mechanically actuated with and from the rotor, with means 105 for adjusting said interrupter for timing purposes, so as to simultaneously vary the sparking point on each and every one of the impulses delivered from the coil to the distributor, for each revolution of the rotor and 110 for each complete operation of the distributor.

60. An apparatus for distributing ignition current from a trunk point to a plurality of spark devices including in combination, a 115 trunk conductor, a plurality of receiving terminals each of which is adapted to be connected to a spark device, said terminals being arranged in a plurality of groups, and means for selecting one of said groups of 120 receiving terminals and then another and simultaneously connecting a selected receiving terminal in said group to said trunk conductor.

61. An apparatus for distributing ignition 125 current from a trunk point to a plurality of spark devices including in combination, a trunk conductor, a plurality of receiving terminals each of which is connected to a spark device, said receiving terminals being ar- 130

ranged in a plurality of groups, a series of mechanically separated but electrically connected contacts connected with said trunk conductor, and means for selecting one of 5 said groups of receiving terminals and then another and simultaneously connecting a terminal of said group with a unit contact connected with the trunk conductor.

62. An apparatus for distributing ignition current from a trunk point to a plurality of 10 spark devices including in combination, a plurality of receiving terminals each of which is adapted to be connected to the spark device of an internal combustion engine, said receiving terminals being ar- 15

ranged in a plurality of groups, a series of contacts mechanically separated but electrically connected together and to said trunk conductor, and means for simultaneously selecting one of said groups of receiving terminals at a time and connecting a unit terminal therein with an associated unit contact in said series of contacts connected to 20 said trunk conductor.

In testimony whereof I hereunto affix my 25 signature in the presence of two witnesses.

CHARLES THOMAS MASON.
